Patented Dec. 26, 1916.

UNITED STATES PATENT OFFICE.

JAMES MATTHEWS, OF VANCOUVER, BRITISH COLUMBIA, CANADA.

EXCAVATING-BUCKET.

1,209,988.

Specification of Letters Patent. Patented Dec. 26, 1916.

Application filed September 11, 1916. Serial No. 119,502.

To all whom it may concern:

Be it known that I, JAMES MATTHEWS, a citizen of the Dominion of Canada, residing at Vancouver, in the Province of British Columbia, Canada, have invented certain new and useful Improvements in Excavating-Buckets, of which the following is a specification.

This invention relates to an excavating and conveyer bucket of that class which is mounted on a carriage for conveyance along an aerial standing line reaching from the place of deposit over the ground to be excavated; and the improvements are directed to a means for automatically latching the bucket to the carriage in a horizontal or load carrying position; to a means for automatically securing the carriage on the standing line, at any predetermined position thereon against backward movement, where it may be desired to dump the load, to a means for automatically releasing the latch by which the bucket is sustained to the carriage in the horizontal or load carrying position, to a means for imparting a jar or shock to the bucket when the same is up-tilted to facilitate the delivery of its load, and to the means whereby the up-tilting of the bucket will effect release of the carriage from the standing line and permit its return to the place of excavation. The particular means by which these several features of the invention are carried into effect are fully set forth in the following specification, reference being made to the drawings by which it is accompanied, in which:

Figure 1 is a more or less diagrammatic elevation to a reduced scale showing the relation of the bucket to the aerial standing line and to the hauling line. Fig. 2 is a vertical longitudinal section of the bucket and its carriage, and Fig. 3 is an end elevation of the same from the front end.

In these drawings 2 represents the standing line which extends from an anchorage 3 on the farther side of the place of excavation 4 to a gin pole 5 adjacent the place of deposit. Over a sheave 6 on this pole 5 the line 2 passes to the donkey engine 7, with provision whereby the aerial line may be slackened to lower it to the ground level, as shown by the full lines in Fig. 1, or tightened to lift it therefrom, as shown by the dot and dash lines in the same figure.

The bucket 10 which is substantially rec-

tangular and open at the front or excavating end and at the top adjacent this end, is suspended on trunnion pins 11 from a carriage 8 which runs on sheaves 9 along the standing line 2. The axis of suspension of the bucket is below and backward from its loaded center of gravity so that it is unstably suspended with a preponderating weight forward of its pivot.

The front portion of the carriage 8 is projected downward to check upward movement of the forward end of the bucket 10 beyond the horizontal position, and pivotally mounted at 25 in the downwardly projected front end of the carriage is a hook or latch member 26, which is designed to engage and retain a bail or loop 27 secured to and extending across the front end of the bucket. This hook member 26 is weighted that it will normally assume the latched position and its underside is angled where the bail engages it that it will automatically move to permit entrance and latching of the bail. From this hook member an arm 28 projects upward, adjacent the pivot, to the end of which arm a release rod 29 may be pin-connected at 30 to project through a trunnion mounted bearing 31 in the front end of the frame of the carriage 8 adjacent the standing line 2 where it passes through the carriage.

The hauling line 12 is connected at 14 by a bail or bridle chain, to each side of the bucket 10 adjacent its excavating edge, and the haul-back line 15 is connected to a double chain bridle 16 which passes over sheaves 17 on the forward end of the carriage 8 and is connected at 18 to the top of the forward end of the bucket.

On the standing line 2 at any position where it may be desired to deposit the load of the bucket a member 23 is removably secured, the face of which member will engage the end of the release rod 29 and will press it in, to effect release of the hook or latch 26 from its engagement with the bail of the bucket and permit the front end of the bucket to fall to deposit its load.

Secured across the back end of the bucket is a stop 19 which, when the bucket swings free on its pivot, will engage a corresponding stop 20 secured to the carriage and will arrest movement of the bucket slightly before it attains the vertical position. The principal object of this stop is to impart a

sharp shock or check to the bucket when it is uptilted and thereby loosen its contents and permit the bucket to be more completely emptied. The adherence of the earth to the 5 walls is an objection with existing buckets and a considerable proportion of the load is frequently returned to the place of excavation.

To secure the carriage at any desired position on the standing line where it may be desired to deliver the contents of the bucket, a latch member 22 is pivotally mounted at 21 in the forward part of the carriage, the end of which latch 22 is designed to engage the 10 shoulderered backward edge of the member 23 by which release of the bucket is effected in the manner just described, and projecting downward from its latch member adjacent the pivot is a portion 24 which projects in 15 the path of the after end of the bucket 10 as it uptilts to deposit its contents, so that as the bucket deposits its load the carriage is released from the standing line and the carriage 20 is free to move back along the line 2 to the place of excavation for another load.

In use, the carriage 8 with its bucket 10 is either drawn by the haul-back line 15, or when the nature of the ground allows, falls by gravity along the standing line 2 from 30 the place of deposit to the place of excavation. When at the place of excavation the standing line 2 is lowered to enable the bucket to reach the surface of the ground which it is desired to excavate, and the excavating edge of the bucket is directly drawn 35 over the ground by the hauling line 2. While the carriage 8 is moving out to the place of excavation and while the bucket is filling, the front end of it is not necessarily 40 latched to the hook member 26 of the carriage but its excavating edge is free to adapt itself to the tension of the hauling line to effectively scoop the bucket full; but when the bucket is full, its after end being loaded 45 will settle down and the tension of the hauling line inclining upward from the hollow of the excavation will lift the front end of the bucket into the latching position and the bail 27 will be automatically latched to 50 the hook 26. When this latching is effected the operator at the donkey will tighten his standing line 2 to lift the bucket clear of the ground and it will be drawn to the place of deposit. On reaching the place of deposit, 55 the release rod 29 will engage the face of the member 23 secured on the standing line and the hook member 26 will be withdrawn from engagement with the bail 27 of the bucket, the front end of which is then free to fall 60 to deposit the load when the tension on the hauling line is relaxed, but although the bucket is free to empty itself the carriage 8 is still secured by the latch 22 to the member 23 until the after end of the uptilted 65 bucket engages the end 24 of the latch 22

and moves it forward to lift the latch and release the carriage which is then free to return to the place of excavation for another load.

Having now particularly described my 70 invention, I hereby declare that what I claim as new and desire to be protected in by Letters Patent, is:

1. An excavating and conveyer bucket, comprising the combination with a carriage 75 adapted to travel on an overhead track, said carriage having relatively rigid dependent arms spaced apart, of an excavator bucket pivotally mounted to and between said arms, said carriage having a depending bucket 80 engaging abutment to engage the forward end of the bucket and limit its elevating movement, a latch device mounted on said carriage, a bail on said bucket to engage with said latch device, an adjustable shoulder member adapted to be secured to the overhead track, a latch releasing rod connected with said latch and adapted to engage said shoulder member to release said latch and a carriage latching device for 90 latching the carriage to said shoulder member at the time of release of said bucket latch, and holding lines connected with said bucket and carriage.

2. An excavator and conveyer bucket, 95 comprising the combination with a carriage adapted to travel on an overhead track, of an excavator bucket pivotally suspended from the carriage, means for automatically latching the front or excavating end of the 100 bucket to the carriage to sustain the bucket in an unstable position, and means secured on the overhead track for automatically effecting release of the bucket retaining means, said bucket latching means comprising a 105 weighted latch lever pivotally mounted on the carriage, a reciprocating latch release rod mounted on the carriage and adapted to move said latch lever to the releasing position, said latch release rod adapted to engage said release effecting means when the carriage is drawn into juxtaposition thereto.

3. An excavating and conveyer bucket, comprising the combination with a carriage 115 adapted to travel on an overhead track, said carriage having relatively rigid depending arms, of an excavator bucket pivotally mounted on and between said arms to swing from the carriage, means for latching the front or excavating end of the bucket to 120 the carriage, means for effecting release of the bucket latching means, and a stop carried by and projecting between said arms, together with a stop on the rear end of the bucket, said bucket stop adapted to engage said arm carried stop with jarring impact when said bucket is released.

4. An excavating and conveyer bucket, comprising the combination with a carriage 125 adapted to move on an overhead track, of 130

an excavator bucket pivotally mounted to swing from the carriage, a latch member pivotally mounted adjacent the front end of the carriage and adapted to engage a 5 shouldered projection secured on the overhead track, said latch member being downwardly produced from its pivot to project in the path of the after end of the bucket when the same swings free on its pivot to

10 the emptying position.

5. An excavating and conveyer bucket, comprising the combination with a carriage adapted to move on an overhead track, of an excavator bucket pivotally mounted to 15 swing from the carriage, a hauling line directly connected to the front end of the bucket and a haul-back line passing from the rear end of the carriage over sheaves

adjacent the front end of the same and connected to the front end of the bucket.

20

6. An excavating and conveyer bucket, comprising the combination with a carriage adapted to move on an overhead track, of an excavator bucket pivotally mounted to swing from the carriage, of a latch automatically securing the front end of the bucket to the carriage when the same is lifted into engagement with the latch, and means for lifting the front end of the bucket into latching engagement, said means comprising a haul-back line passing from the back end of the carriage over sheaves at the front end and connected to the front end of the bucket.
